Patented Jan. 13, 1914.

UNITED STATES PATENT OFFICE.

ELMER A. BENSON, OF PERU, ILLINOIS.

FASTENER.

1,084,528.

Specification of Letters Patent.

Patented Jan. 13, 1914.

Application filed February 17, 1912. Serial No. 678,183.

To all whom it may concern:

Be it known that I, ELMER A. BENSON, a citizen of the United States, residing at Peru, in the county of La Salle and State of Illinois, have invented new and useful Improvements in Fasteners, of which the following is a specification.

The present invention relates to improvements in fastening devices.

10 In carrying out my invention it is my purpose to provide a fastening device for shoes, leggings, gloves or the like, the same embodying a button and a rotatable fastener for the button wherein the employment of button holes as well as the hooks for fastening the button within the button hole is dispensed with.

With the above recited objects in view, and others of a similar nature which will be 20 more fully understood as the nature of the invention progresses, the improvement resides in the novel construction, combination and arrangement of parts set forth in and falling within the scope of the appended 25 claim.

In the drawing, Figure 1 is a view illustrating my improvement applied to a shoe. Fig. 2 is an enlarged sectional view upon the line 2—2 of Fig. 1. Fig. 3 is a bottom 30 plan view of a fastener. Fig. 4 is a detail sectional view of the casing for the fastening. Fig. 5 is a perspective view of the button.

In the drawing I have illustrated my improved fastener as applied to a shoe but as heretofore stated the fastener is not to be thus limited in its useful application, as the same may be applied upon various other articles.

40 Referring now to the drawing in detail, the numeral 1 designates the shoe. The quarter of the vamp is provided at spaced intervals with buttons. These buttons embody a head 3 having a stem 4 and a base 5. 45 The base is integrally formed with a plurality of depending prongs. The prongs are formed of bendable material and are adapted after being inserted within the quarter of the vamp, to be bent and clenched against 50 the quarter, as clearly illustrated in Fig. 2 of the drawing. By this arrangement it will be noted that the employment of special securing means for retaining the buttons upon the shoe is entirely dispensed with and 55 further that the buttons may be easily and

quickly attached to or removed from the shoe, as desired.

The numeral 7 designates the button securing member. This member is positioned upon the portion of the quarter over-lapping 60 that provided with the buttons 2. The member 7, has, what may be termed its shank 8 hollow and is constructed of a single piece of suitable metal, stamped to provide a base 9 having a continuous flange 10 which 65 is provided by over-lapping one of the portions of the member above the lower portions, and the said member is then bent upwardly to provide the shank proper. The base 9 is arranged above its flange 10 and is 70 centrally provided with a reduced opening 11, the same being of an area equaling the thickness of the stem 4 of the button 2. The base is further provided with an enlarged opening 12 of an area slightly greater than 75 the head 3 of the button, and the base is provided with a passage or opening 13 which forms a communication between the openings 11 and 12, thus providing the base of the button with what may be termed a key 80 hole slot. The upper portion of the shank 8 is slotted, and the portions of the metal between the said slits are curved outwardly and downwardly to provide a plurality of 85 tongues 14, the latter being adapted to engage with the incurved edges 17 provided by the top 18 of the casing. The top 18 may be of any ornamental design, and may be constructed of some thin metal and is preferably cup-shaped. 90

The numeral 16 designates a reinforcing member for the top. This member 16 is constructed of some resilient material which has a greater strength than the metal from which the top is constructed. The member 95 16 embodies a centrally curved portion which contacts with the central portion of the underface of the top, and the member is further provided with an outwardly extending downwardly curved portion 15 100 which is adapted to be arranged between the tongues 14 and the incurved portion 17 of the top 18 and to exert a tension therebetween to retain, together with its curved central portion, the incurved edge of the top 105 18 tightly against the shank 7 as well as against the shoe 1. By such an arrangement, it will be noted that the head is always under the tension of the resilient reinforcing member so that its edge cannot accidentally 110

- become displaced from the tongues 14, and in connecting the securing member to the button, the member 7 is rotated until the enlarged opening of the base 18 is arranged 5 over the head 3 of the bottom 2. The member 7 is then rotated until the stem 4 of the button 2 is brought to within the reduced opening 11 of the base. As has been stated the shank 8 is constructed of some 10 suitable metal, which of course provides a certain amount of resiliency, and as the base is elevated above the flange 10, the same will exert a tension against the head 3 of the button 2.
- 15 Having thus described the invention what I claim is:—
- The herein described construction of fastening devices for buttons, including in combination with a button having a stem, a rotatable member comprising a fastener for the button, said member embodying a hollow shank having a base provided with an enlarged opening and a reduced opening communicating with the enlarged opening, 20 the said shank being formed with an out-turned flange which is arranged below the base, the opposite edge of the shank being slotted and the portions of the metal between the slits being curved outwardly and
- 25

downwardly to provide tongues, a cup-shaped top constructed of flexible material having an incurved edge which is adapted to be arranged between the tongues and the shank of the member, a reinforcing member constructed of resilient material, said member having a central curved portion which is adapted to contact with the underface of the top and being further provided with an outwardly extending downwardly curved end which is arranged between the tongues of the 40 shank and the incurved edge of the top and adapted to exert a tension upon the top and the said incurved edge, for the purpose set forth, and the head of the button adapted to be received within the enlarged opening 45 of the base of the said securing member and the securing member adapted to be rotated to bring the stem of the button to within the reduced opening of the base to permit of its head resting upon the elevated 50 base.

In testimony whereof I affix my signature in presence of two witnesses.

ELMER A. BENSON.
